DES. 2461

Chas. Mills & Sons, of same place,

Letters Patent No. 2461. Date Oct. 25, 1866.

Design for a Candy Figure.

The Schedule referred to in these Letters Patent and making part of the same.

To all whom it may concern:

Be it known that I, Leonhardt Schulze of the City of Philadelphia and State of Pennsylvania have originated and designed a new figure for casting in Candy of which the following is a full and exact description, reference being had to the accompanying photograph making part of this Specification.

The Design relates to that class of figures which are cast hollow of transparent or opaque candy and are extensively used as tops for ornamenting Christmas trees etc. They are made by pouring the heated liquid candy into a metallic mould, after that portion of the candy which comes in contact with the mould, has crystallized and hardened to form a shell of sufficient strength, the inner, still liquid portion is poured out again, and the hollow casting is then removed from the mould, which to this end is arranged to separate in two or more parts.

The figure represents a Fireman, his posture and detail of configuration being fully shown in the accompanying photograph.

What I claim as my invention and desire to secure by Letters Patent is,

The Design for a Candy Figure herein set forth.
